Primary Examiner — Selina Sikder(74) *Attorney, Agent, or Firm* — Polsinelli PC(57) **CLAIM**

We claim the ornamental design for a control device, as shown and described.

DESCRIPTION

FIG. 1 is a perspective view of a first embodiment of a control device, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

FIG. 8 is a perspective view of a second embodiment of a control device, the second embodiment being the same as the first embodiment except that the broken lines are used to illustrate unclaimed portions of the control device;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof; and,

FIG. 14 is a bottom plan view thereof.

Broken lines are for illustrating unclaimed portions of the control device and form no part of the claimed design.
